DESIGN FOR A VANITY CASE OR SIMILAR ARTICLE

Fred Spitalny, Elizabeth, N. J.

Application January 28, 1938, Serial No. 74,628

Term of patent 3½ years

To all whom it may concern:

Be it known that I, Fred Spitalny, a citizen of the United States, residing at Elizabeth, in the county of Union and State of New Jersey, have invented a new, original, and ornamental Design for a Vanity Case or Similar Article, of which the following is a specification, reference being had to the accompanying drawing, forming part thereof.

The figure is a perspective view of a vanity case or similar article, showing my new design.

The side of the vanity case not shown is substantially like the side shown in the drawing.

The edges not shown have substantially the same surface decoration as the edge shown.

I claim:

The ornamental design for a vanity case or similar article, as shown and described.

FRED SPITALNY.
